WAVE SIGNALING SYSTEM

John Kelly Johnson, Rye, N. Y., assignor to Hazelton Corporation, Jersey City, N. J., a corporation of Delaware

Application November 15, 1934, Serial No. 753,103

4 Claims. (Cl. 250—20)

This invention relates to wave signaling systems wherein modulated carrier wave signals are transmitted over cable conductors between portions of signaling apparatus situated some distance apart, as in different portions of a room or building. More especially the invention pertains to remotely controlled tuned radio broadcast receivers in which the input portion is housed in a portable control unit connected by cable conductors to the receiver proper.

An object of the invention is to provide an improved form of remote coupling over cable conductors, which is simplified as to construction and manipulation, and which is highly efficient, as compared to known couplings for similar purposes, throughout a relatively wide range of frequencies such as the complete frequency operating range of a multi-wave band receiver. A feature of the invention resides in utilization of the capacity inherent between the cable conductors in part to effect the desired coupling.

The superheterodyne type of receiver has been adapted to remote control operation by housing the tuned radio frequency amplifier and oscillator-modulator portions in a small portable unit cable-connected to the main receiver chassis containing the intermediate frequency, detector and audio frequency units. Of necessity the antenna and ground connections are wired directly to terminals on the main chassis due to its more or less permanent location as compared to the portable circuit. The signals picked up by the antenna, however, must be first impressed on the input portion of the receiver contained in the portable unit, and, to this end, they are conveyed thereto over the cable conductors.

A problem is thus presented, particularly in multi-wave band receivers, of providing a coupling from the antenna over the cable conductors to the tuned input, which is simple in construction and manipulation as well as efficient and effective throughout the wave band or bands for which the receiver is tunable. It has been proposed by way of solution of this problem to connect the antenna and ground terminals at the chassis to respective conductors of a cable pair, and to connect the remote terminals of this cable pair to the tuned input of the remote control unit in an orthodox manner, as for example, through a transformer. The cable thus becomes but an extension of the antenna and ground lead-in conductors.

This form of connection has, however, been demonstrated in practice to introduce losses so serious as greatly to impair performance of the

apparatus as a whole. One reason for this is that substantially the entire open circuit signal voltage of the antenna circuit is impressed between the cable conductors, which, due to the relatively large capacity inherent between conductors, greatly attenuates the signals prior to applying them to the tuned input circuit.

In an effort to eliminate this defect, it has been proposed further to couple the antenna circuit to the cable through a step-down transformer and additionally to employ a step-up transformer coupling between the cable and the tuned input to the receiver. The thought here is to convert the relatively high voltage-low current energy of the antenna circuit, to low voltage-high current for transmission over the cable, thereby to minimize the aforementioned high frequency cable losses, the signals being thereafter reconverted by the step-up transformer to the high voltage-low current required by the tuned input. With this arrangement the coupling efficiency varies markedly with frequency despite the introduction of disproportionately expensive and complicated circuits in an effort to offset this effect. This variation in efficiency, which is particularly noticeable in the successive wave bands of a multi-wave band receiver, results from the well understood action of the antenna coupling transformer and antenna impedance relations as follows:

The antenna impedance is in general capacitively reactive throughout the frequency range or ranges of operation. The transformer impedance, on the other hand, is inductively reactive. The antenna circuit will thus be subject to resonance at some fixed frequency at which the antenna circuit is most responsive. Accordingly as the reception frequency is varied by tuning with respect to the fixed frequency of antenna circuit resonance, the effectiveness of signal transfer to the tuned input circuit will vary correspondingly.

Although this variation in effectiveness of coupling with reception frequency may be minimized to some extent by suitable design, as by most effectively allocating the fixed resonance of the antenna circuit and the employment of resistance damping, it nevertheless remains a serious source of loss in efficiency, particularly at the lower frequency ranges of a multi-wave band receiver due to resulting low transformer efficiency at such frequencies.

This loss in transformer efficiency is in fact so excessive that it becomes necessary in multi-wave band receivers employing the mentioned

transformer couplings to the cable, to provide at the tuned input in the remote control unit, separate step-up transformers individually suitable for each wave band of operation. Not only is this 5 an unduly expensive construction, but in addition further complication and expense are necessarily incurred by the requirement for suitable switching apparatus in the control unit adapted to connect the transformers individually in the receiver 10 circuit both as to their primary and secondary coils for selection of a given wave band.

For most effective operation a similar arrangement of transformers and switching should be employed at the main receiver chassis to couple 15 the antenna circuit to the cable. Since this additional switching at the main receiver chassis would, however, destroy the feature of remote control operation, the practice has been to employ a permanently tapped coil in the antenna 20 circuit despite the resulting loss in efficiency at the lower frequency bands of operation.

I propose, and it is upon this that my invention is predicated, to eliminate the mentioned disadvantages inherent in arrangements heretofore 25 suggested, by capacitively coupling the antenna circuit to the cable and over the cable to the tuned input of the receiver. To this end I propose, in the preferred modification of my invention, to interpose fixed condensers of suitably 30 chosen values in both the antenna circuit and the tuned input circuit. I further propose to bridge these condensers respectively between opposite ends of a cable conductor and the metallic sheath 35 housing the conductors.

Within the operating range of the receiver the 40 cable usually will be electrically short and its distributed capacity thus effectively lumped. Hence the capacities of the mentioned coupling condensers and that of the cable are equivalently 45 that of a single lumped condenser having a capacity equal to the sum of the capacities of the coupling condensers and of the cable. The antenna circuit is thus in effect coupled to the tuned input circuit through a single lumped coupling condenser of appropriately chosen value.

With this arrangement the coupling impedance assumes the same character as that of the antenna, that is, both are substantially pure capacities throughout the operating frequency 50 range. Thus the fraction of the total signal voltage impinging on the antenna which is impressed on the coupling impedance, tends to be substantially constant and independent of frequency and equal to the ratio of the coupling capacity to 55 sum of the antenna and coupling capacities.

Moreover, since in the tuned input circuit the capacity of the tuning condenser is now in series with the coupling capacity, the coupling from the antenna circuit to the tuned input will 60 be the same for a given dial setting of the tuning condenser for all wave bands of operation in a multi-wave band receiver. This results from the fact that the coefficient of coupling depends exclusively on the antenna capacity, the coupling 65 capacity, and the tuning capacity in accordance with the well understood definition for coefficient of capacitive coupling. For a given setting of the tuning condenser the coefficient of coupling will therefore be the same for all wave bands of operation.

Owing to the relatively high efficiency of this type of coupling for the various wave bands of reception, the necessity for switching operations at the main receiver chassis is avoided, and those 75 at the remote control unit reduced to the mini-

mum of coil changes in the tuned circuits only, thereby to adjust the operation from one wave band to another as desired.

The single figure of the drawing shows schematically a remotely controlled, multi-wave 5 band, superheterodyne receiver employing the invention for capacitively coupling the antenna circuit over cable conductors to the tuned input of the receiver, and also for capacitively coupling the intermediate frequency output in the remote 10 control portion of the receiver back over cable conductors to the receiver proper. The portion of the receiver circuit requisite to full understanding of the invention is shown in the form of a circuit diagram. 15

The system of the drawing comprises broadly a main receiver unit 1, a remote control unit 2, and a shielded cable 3 containing conductors such as 4 and 5, housed in a metal sheath 6 and appropriately connecting the main receiver unit to 20 the remote control unit.

The receiving system includes an antenna 7 and ground 8 arranged in a circuit coupled, in a manner to be explained, over the cable to the tunable input circuit 9 of a vacuum tube 10 constituting a stage of tuned radio frequency amplification. The reception frequency output of tube 10, is selectively applied by a tunable circuit 11, generally similar to 9, to the input of a multi-grid vacuum tube 12 operating as a combined oscillator-modulator, the former by virtue of a tuned impedance 13 regeneratively coupling certain of its electrodes. The intermediate frequency output of tube 12 is selectively applied, in a manner to be explained, over cable conductor 25 5 to the input of a vacuum tube 14 operating as a stage of intermediate frequency amplification in the main receiver unit, the remainder of which, comprising additional stages of intermediate frequency amplification, detector and audio frequency amplification, is indicated schematically by rectangles 15, 16 and 17 respectively. The terminating loud speaker 18 may be mounted on the receiver chassis or located elsewhere as desired. The receiver is energized from the usual power rectifier indicated by rectangle 19, energized over a supply line, and in turn supplying the receiver over conductors such as 21.

Considering the remote control unit somewhat more in detail, the tuned input circuit 9 comprises a fixed condenser C_1 , and a pair of coils 20' and 21' individually shunted by padding condensers 22 and 23 respectively, bridged in series across a variable condenser 24 connected between the control grid 25 and cathode 26 of tube 10. The circuit is tunable by condenser 24 throughout two distinct frequency bands, selection of either of which is under control of a switch 27 adapted to short circuit the lower coil 21'. Reception occurs within the upper frequency band with switch 27 closed, and at the lower frequency band with the switch open.

Tuned circuits 11 and 13 are generally similar in construction and arrangement to circuit 9. The band selection switches corresponding to 27 and the rotors of the variable condensers corresponding to 24, are, for the mentioned tuned circuits, mechanically ganged to unitary controls 28 and 29 respectively, for simultaneously adjusting the reception band and the tuning respectively of the several circuits. The padding condensers of tuned circuits 11 and 13 corresponding to condensers 22 and 23 of circuit 9, are semi-adjustable and serve to align the circuits for single dial tuning. Condenser 35, hav-

ing a capacity about equal to the sum of the combined capacities C_1 and the distributed capacity, C , of the cable, provides at least approximate alignment between circuits 11 and 9.

The output or plate circuit of tube 10 is coupled capacitively through condenser 30, and inductively through transformer 31, to circuit 11 bridged between the signal control grid of tube 12 and the common cathode lead 32. The design is such that the capacitive coupling opposes the inductive coupling for reception at the lower frequency band, the couplings being, however, additive for reception at the upper frequency band. In this way the gain or amplification is maintained reasonably uniform throughout both reception bands.

For generating heterodyne oscillations, circuit 13 is connected between the inner grid of tube 12 and the cathode lead 32, a combined inductive and capacitive regenerative coupling to the second grid being provided by transformer 33 and condensers 34. Inductance 56 is a radio-frequency choke. Here again resort is had to the compound type of coupling to achieve reasonably uniform gain in the oscillator-modulator throughout both reception frequency bands. Signal modulation is effected by the action of the inner grid blocking condenser 35 and leak resistor 36 connected from the inner grid to the cathode.

The remote control circuit is provided with the usual resistors such as 35', 36, 37, 38, 39 and by-pass condensers, such as 40, 41, 42 and 43, for suitably adjusting the potentials of the tube electrodes, by-passing and filtering high frequency currents, etc.

The common cathode lead 32 is grounded to the metallic sheath 6 of cable 3, this sheath in turn being grounded at 44 at the main receiver chassis. Only such cable conductors are shown as are directly involved in the present invention. They are conductors 4 and 5 connected to the grid circuit of tube 10 and to the plate circuit of tube 12 respectively, as is explained herein-after. It will be understood, however, that there will be present in the cable other conductors for suitably energizing the electrodes of tubes 10 and 12, and for securing at the control unit such operations as switching on and off of the power supply, volume control, etc.

For purposes of this invention the antenna 7 is connected to ground 8 through a resistance 45, and to cable conductor 4 through a blocking condenser 46, the latter in order to prevent grounding at 8 of negative biasing voltage applied by the power unit over conductors 47 and 5 to the grids of tubes 10 and 12.

Bridged between the conductor 4 and ground at the main receiver chassis, is a condenser C_1 similar to condenser C_2 serially included at the remote control unit 2 in the tuned input circuit 9, and connected thereto between cable conductor 4 and the grounded sheath 6. Condensers C_1 together with the distributed capacity inherent between cable conductor 4 and grounded sheath 6, indicated by capacities C , serve to couple the antenna circuit 7, 8 capacitively to the tuned circuit 9 in accordance with the invention.

In the usual installation cable 3 will be electrically short with respect to the wavelengths to which the receiver is tunable. The distributed capacity C thus functions substantially as a single lumped capacity connected in parallel with the two capacities C_1 . The antenna circuit 7, 8 may therefore be considered as coupled to tuned cir-

cuit 9 through a single capacity equal to the sum of capacities C_1 , and the total distributed capacity inherent between conductor 4 and metallic sheath 6.

In a capacitively coupled circuit, such as that under consideration, the coefficient of coupling depends only on the resultant capacities individual to the antenna and tuned circuits and the mutual coupling capacity. All of these capacities are substantially fixed with the exception of the variable tuning capacity 24 which, however, for a given dial setting, introduces the same capacity into the tuned circuit for operation in either the upper or lower frequency bands of reception. It follows from this that the coupling coefficient, and hence the efficiency of signal transfer from the antenna circuit 7, 8 to the tuned input circuit 9, will be substantially the same in both the upper and lower reception bands for like dial settings of condenser 24.

Resistance 45, arranged in the antenna circuit effectively in shunt to the antenna coupling capacities, assists in minimizing such tuning misalignment of tunable circuit 9 with respect to tunable circuits 11 and 13 as might otherwise occur in consequence of variations in antenna capacities within the range encountered in practice. This resistance serves additionally to reduce variation in coupling efficiency with adjustment of the tuning condenser 24, and also to by-pass interfering currents of relatively low frequencies, such as may be picked up by the antenna.

A coupling of the same character as that described above, is employed to couple the intermediate frequency output of the oscillator-modulator tube 12 over cable conductor 5 to the input of the intermediate frequency amplifier tube 14. To this end there is directly connected between the anode of tube 12 and the grounded cathode lead 32, a tuned circuit 48 consisting of a semi-adjustable condenser 49 bridged across a coil 50 and a fixed condenser C_2 in series. Condenser C_2 is in turn bridged between cable conductor 5 and the grounded metallic sheath 6. A similar condenser C_2 is in turn bridged between conductor 5 and ground at the main receiver chassis. This latter condenser C_2 is serially included in a resonant circuit 51 inductively coupled by the mutual inductance M to a second resonant circuit 52 connected between grid and cathode of tube 14.

The system comprising circuits 48, 51 and 52 constitutes a triple tuned coupling system coupling the output of tube 12 to the input of tube 14. This system is tuned to the intermediate frequency by means of the semi-adjustable condensers 49, 53, 54. Since, as stated, cable 3 is, in general, electrically short in relation to the wavelengths at which the receiver is operable, the coupling between circuits 48 and 51 is equivalent to that of a single lumped capacity equal to the sum of the two capacities C_2 supplemented by the total distributed capacity C inherent between cable conductor 5 and sheath 6, considered as a lumped capacity.

The magnitudes of condensers C_1 and C_2 , will, of course, depend upon the cable capacity, the design of the circuits to be coupled and the degree of coupling required. For example, capacities of 500 micro-microfarads ($\mu\mu F$) were found suitable for each of condensers C_1 and C_2 for a particular installation incorporating the circuit of the drawing. The total coupling capacity was 75

therefore in each instance that of the cable conductors plus 1000 μ uf.

I claim:

- 5 1. In a wave signaling system: a signal translating circuit tunable throughout a plurality of frequency bands, an antenna circuit spaced therefrom, said antenna circuit being capacitively reactive at the frequencies of tuning of said tunable circuit, a pair of cable conductors extending between said circuits, and means capacitively coupling said circuits comprising, the capacity inherent between said cable conductors supplemented by capacities individual to said circuits and bridged between said conductors thereat respectively.
- 10 2. In a wave signaling system, a circuit, means for tuning said circuit throughout a plurality of frequency bands, an antenna circuit remote therefrom, said antenna circuit being capacitively reactive at the frequencies of tuning of said tunable circuit, a pair of cable conductors extending between said circuits, and means capacitively coupling said circuits comprising, the capacity inherent between said cable conductors supplemented by the capacity of condensers individual to said antenna and tuned circuits respectively, said condensers being bridged between opposite terminals of said cable conductors.
- 15 3. In a wave signaling system, a circuit tunable throughout a plurality of frequency bands

by a variable condenser, a plurality of coils and switching means for connecting in said circuit a coil appropriate to each of said frequency bands, an antenna circuit remote from said tuned circuit, a pair of cable conductors extending between said circuits, and means capacitively coupling said circuits comprising, the capacity inherent between said cable conductors supplemented by capacities individual to said circuits and bridged between said conductors thereat respectively. 5 10

4. In a wave signaling system, a receiver comprising two units physically removed from each other and an antenna circuit, each of said units including input and output circuits, a cable including two conductors surrounded by a third conductor, means capacitively coupling said antenna circuit to the input circuit of one of said units comprising the capacitance between one of said two conductors and said third conductor and additional capacitance bridged between said one of said two conductors and said third conductor, and means capacitively coupling the output circuit of said one of said units to the input circuit of the other of said units comprising the capacitance between the other of said two conductors and said third conductor and additional capacitance bridged between said other of said two conductors and said third conductor. 15 20 25

JOHN KELLY JOHNSON. 30
